DESIGN FOR A TELEVISION SCREEN PROTECTOR

Thomas Fortino, Belleville, N. J.

Application July 17, 1947, Serial No. 140,341

Term of patent 7 years

(Cl. D26—14)

To all whom it may concern:

Be it known that I Thomas Fortino, a citizen of the United States, residing at Belleville, in the county of Essex and State of New Jersey, have invented a new, original, and ornamental Design for a Television Screen Protector, of which the following is a specification, reference being had to the accompanying drawing, forming part thereof.

Fig. 3 is a view in end elevation of my novel protector.

I claim:

The ornamental design for a television screen protector, as shown.

THOMAS FORTINO.
